UNITED STATES PATENT OFFICE.

JOSEPH M. TOEPFERT AND CHARLES H. DEPPING, OF HOLYOKE,
MASSACHUSETTS

TEMPORARY BINDER.

SPECIFICATION forming part of Letters Patent No. 665,706, dated January 8, 1901.

Application filed July 5, 1900. Serial No. 22,516. (No model.)

To all whom it may concern:

Be it known that we, JOSEPH M. TOEPFERT and CHARLES H. DEPPING, citizens of the United States, residing at Holyoke, in the 5 county of Hampden, State of Massachusetts, have invented a new and useful Improvement in Temporary Binders, which improvement is fully set forth in the following specification and accompanying drawings.

10 Our invention consists of an improved construction of a temporary binder that is adapted to contain and hold a number of separate leaves to serve as a note-book.

15 Our invention further consists of novel details of construction, all as will be hereinafter fully described and claimed.

Figure 1 represents a perspective view of a temporary binder embodying our invention. Fig. 2 represents a plan view of the upper 20 portion thereof with the top cover and clamping-plate open. Fig. 3 represents a front elevation of the upper portion thereof with the top cover and clamping-plate closed. Fig. 4 represents a section taken on line $x-x$, Fig. 2, 25 with the top cover and clamping-plate closed. Fig. 5 represents a section taken on line $x-x$, Fig. 2, with the top cover beneath the back cover and clamping-plate open. Fig. 6 represents a fragmentary detailed perspective 30 view.

Similar letters of reference indicate corresponding parts in the figures.

Referring to the drawings, A designates the back cover of the binder, and B the front cover 35 thereof, the same being joined by the hinge C, which permits the front cover to be turned beneath the back cover, as shown in Fig. 5, so that when using the note-book as a writing-pad said front cover is out of the way. The back cover A is longer than the front, 40 cover B to extend above the same at the top of the binder, whereby the clamping-plate D, that is supported by the brackets E, can close upon the upper portion of the leaves F, the 45 free edge of said clamping-plate D being situated above the upper edge of the top cover B. The said brackets E have one limb extending along the back of the back cover A, to which they are secured by screws G and 50 nuts H. The said nuts H project upwardly from the front face of the back cover A and

serve as pins to pass through the perforations in the leaves of the note-book to hold said leaves in place. The said brackets, it will be seen, project beyond the upper ends of the 55 back cover A and are provided with angular limbs that rise above the cover A and which are provided with heads J, conveniently elliptical in shape. The clamping-plate D is hinged to the said heads J of the brackets E 60 conveniently by means of the sockets K upon the plate that receive the pintles L upon said heads J. Between the hinged sockets K of said plate D are spring-fingers M, that engage the face of the heads J to hold the same 65 in the desired position. The said clamping-plate D is also provided with depressions or sockets N, that receive the upper ends of the pins H, as clearly shown in Fig. 4.

The operation is as follows: It will be noted 70 that the springs M in bearing against the face of the head J hold the clamping-plate D either open or closed. When in the closed position, said clamping-plate D effectually prevents the leaves from being removed from the pins, 75 although this can be readily accomplished by swinging the clamping-plate open. The perforated leaves can be readily placed upon or removed from the pins when the clamping-plate is open, and when the clamping-plate 80 and the top cover are closed a compact note-book is formed. In use the top cover B is turned until it lies against the rear face of the back cover A, so as to be out of the way, as will be obvious.

Having thus described our invention, what we claim as new, and desire to secure by Letters Patent, is—

1. A temporary binder consisting of a back cover provided with means for receiving a 90 plurality of leaves, a hinged spring-actuated clamping-plate at the top of said back cover adapted to bear upon said means for receiving the leaves, and a front cover hinged to the side of said back cover; said front cover 95 being shorter than said back cover, whereby its upper edge is situated below the lower edge of the clamping-plate when said parts are closed upon the leaves.

2. A temporary binder, consisting of a back 100 cover provided with means for receiving a plurality of leaves, a movable clamping-plate

at one end of said back cover adapted to engage said means for receiving the leaves, and a front cover-hinged to the side of said back cover, the upper edge of said front cover being situated below the lower edge of said clamping-plate when said parts are closed upon the leaves.

3. In a temporary binder, a back cover provided with pins upon the front side thereof, brackets at one edge of said back cover pro-

vided with heads, and a clamping-plate hinged to said heads and provided with springs engaging the same, said clamping-plate adapted to engage said pins.

JOSEPH M. TOEPFERT.
CHARLES H. DEPPING.
